UNITED STATES PATENT OFFICE.

STEWART A. MINER, OF CAMROSE, ALBERTA, CANADA.

NON-REFILLABLE BOTTLE.

939,430.

Specification of Letters Patent.

Patented Nov. 9, 1909.

Application filed July 3, 1908. Serial No. 441,803.

To all whom it may concern:

Be it known that I, STEWART A. MINER, subject of the King of Great Britain, residing at Camrose, Alberta, Canada, have 5 invented certain new and useful Improvements in Non-Refillable Bottles, of which the following is a specification.

The present invention appertains to bottles, jugs or like necked receptacles for containing liquid, the purpose being to prevent the reuse of the bottle after the same has been emptied, thereby protecting the party placing upon the market a certain brand of goods, as also insuring the consumer obtaining the genuine article, or goods desired.

For a full understanding of the invention and the merits thereof and also to acquire a knowledge of the details of construction and 20 the means for effecting the result, reference is to be had to the following description and accompanying drawings.

While the invention may be adapted to different forms and conditions by changes in 25 the structure and minor details without departing from the spirit or essential features thereof, still the preferred embodiment is shown in the accompanying drawings, in which:

30 Figure 1 is a vertical central section of a bottle provided with safety means embodying the invention. Fig. 2 is a view similar to Fig. 1, showing the bottle tilted, as in the act of pouring off the liquid contents thereof. Fig. 3 is a horizontal section on the line 3—3 of Fig. 1.

Corresponding and like parts are referred to in the following description and indicated in all the views of the drawings by the same 40 reference characters.

The invention is shown applied to a bottle, although it is to be understood that it may be readily adapted to a jug, or other receptacle having a neck.

45 In carrying out my invention I provide a bottle 1 having the usual neck portion 2, which is flared as at 3 to form a chamber 3^a. Within the bottle neck 2 are positioned in spaced relation two partitions, 4 and 8, partition 4 being located at the base of the neck 2 or at the juncture of the same with the body 1, while the partition 8 is preferably in the form of a stopper which is placed in the upper end of the neck 2. The partitions 50 4 and 8 have central vertical bores 4^a and 8^a and also ducts 4^b and 8^b, preferably four in

number, in each of the partitions, said ducts beginning at the bottom outer edges of the partitions and extending upwardly and inwardly terminating at the upper portions 60 of the bores 4^a and 8^a. The partitions 4 and 8 are each provided with stems 6 and 7 respectively which are slidably mounted in the central bores 4^a and 8^a, the same being provided upon their inner adjacent extremities with flanges 5 and 7^a respectively, the former providing a valve for the stem 6 which rests upon a slightly beveled face 4^c formed upon the partition 4. The stem 6 of the valve 5 fits in the bore 4^a and is 70 adapted to slide therein. The valve 5 has its circular edge 5^a extended downwardly and tapered thereby conforming to the valve seat. The valve stem 6 is made hollow and has a weight 6^a therein, said weight being 75 secured from displacement by a plug 6^b placed in the upper end of same, and a seat 6^c at the lower end thereof. The circumferential grooves 6^d and 7^b are made in the outer sides of the stems 6 and 7, said grooves 80 being in such a position as to register with the upper openings of the ducts 4^b and 8^b and to extend above the upper faces of the partitions 4 and 8 when the bottle is tilted in the act of pouring off the liquid contents 85 thereof. The thickened portion 4^a of the partition 4 serves as a guide for the valve stem 6. The stopper or upper partition 8 is secured in the neck of the bottle in any suitable way, preferably by the employment of 90 a catch 9 as is disclosed in the drawings. It is to be understood that the partition 4 may be formed integral with the neck of the bottle as is shown in Fig. 2 of the drawings. The stem 7 is such a length that when the 95 flanged portion 7^a is resting upon the valve or flange 5, the upper end of the stem 7 is flush with the top of the stopper or partition 8 and the bottle may be sealed in any substantial way.

When the bottle or other receptacle is in an upright position the valve 5 is seated upon the partition 4 and the flange 7^a of the stem 7 rests upon the valve or flange 5, thereby preventing the introduction of liquid 105 into the bottle or other receptacle. When it is desired to empty the contents or a part of the contents of the bottle the same is tilted, whereupon the valve 5 is unseated and assumes, together with the stem 7, the 110 position shown in Fig. 2 which discloses the stems 6 and 7 as being moved upwardly and

being prevented from displacement within the partitions 4 and 8 through the medium of the flanges 5 and 7^a. When in this inverted position the liquid will pass out wardly from the body 1 of the bottle through the ducts 4^a, past the groove 6^a into the chamber 3^a of the neck 2, thence through the ducts 8^b formed through the upper partition 8 whence the liquid will be free to leave the bottle by passing within the circumferential groove 7^b.

It will be readily seen from the foregoing description taken in connection with the accompanying drawings, that I have provided a bottle of the character specified which while thoroughly efficient, consists of few parts which are not likely to get out of order and which may be cheaply and easily manufactured. It will also be noted that the two partitions 4 and 8 are similarly formed and that the operative parts connected thereto are of similar formation and operation thereby effecting a closure which may comprise any number of coöperating or independent partitions and stems or may be provided with but one as desired, however, the preferred arrangement in which two are employed is herein described and illustrated.

Having thus described the invention, what is claimed as new is:

1. In a bottle or receptacle of the type set forth, provided with a neck, a partition arranged within said neck and provided

with a central opening, and other openings at the sides of the central opening and upwardly and inwardly inclined and in communication at their upper ends with said central opening, a valve adapted to close downward on said partition and having a stem loose in the central opening of said partition, said stem having a groove in its side to register with the inclined openings of the partition and provide an escape when pouring off the liquid contents of the bottle.

2. A non-refillable bottle comprising a body portion, a neck carried by said body portion and a plurality of partitions each having a central opening and other openings at the sides of the central opening and upwardly and inwardly inclined to terminate at their upper ends with each of said central openings, stems loosely mounted within the central openings in said partitions, said stems having circumferential grooves formed in the sides thereof adjacent their upper ends registered at times with all of the openings in said partitions, and flanges formed on said stems for preventing the displacement of the same and also for the purpose of sealing the openings formed in said partitions.

In testimony whereof I affix my signature in presence of two witnesses.

STEWART A. MINER. [L.S.]
